FREE-CHAIN PLANETARY HOIST

Fredrick W. Coffing, Danville, Ill.

Application November 15, 1935, Serial No. 49,919

42 Claims. (Cl. 254—171)

This invention relates to a chain hoist of the general character illustrated in the prior Patents No. 1,973,844, dated September 18, 1934, and No. 1,999,036, dated April 23, 1935, and is a continuation in part of the copending applications, Serial No. 755,259, filed November 30, 1934, now Patent No. 2,099,676 dated November 23, 1937, and Serial No. 16,365, filed April 15, 1935, now Patent No. 2,044,565, dated June 16, 1936.

10 The chief object of this invention is to embody in a free-chain hoist a planetary power system.

Another object of this invention is to improve the governor constructions illustrated in the aforementioned applications and the invention 15 is illustrated as applied to a lever operable construction, such as shown in the last mentioned copending application, and the latter is improved by a balanced arrangement thereof.

The chief feature of the invention consists in 20 the formation of the hoist, whereby the foregoing objects are accomplished.

Another feature of the invention consists in the planetary type "free-chain" release arrangement.

25 A still further feature of the invention consists in the improved cushion type anchorage of the load chain to the housing and the addition of a chain guard preventing anchorage interference with the chain and/or sprocket, and chain es- 30 capement from the sprocket.

The full nature of the invention will be understood from the accompanying drawings and the following description and claims:

In the drawings, Fig. 1 is a top plan view of 35 a hoist embodying the invention.

Fig. 2 is a sectional view taken on line 2—2 of Figs. 1 and 4 and in the direction of the arrows.

Fig. 3 is a similar view of the planetary ar- 40 rangement, and is taken on line 3—3 of Fig. 4 and in the direction of the arrows.

Fig. 4 is a central sectional view taken at right angles to Figs. 2 and 3 with the governor constructions and the power members removed.

45 Fig. 5 is a side view of one of the governor constructions.

Fig. 6 is a skeleton sectional view of a modified form of the invention showing an auxiliary housing for the power discs and power lever re- 50 turning springs.

Fig. 7 is a perspective view on a smaller scale of a modified form of lever returning spring guard, illustrated in Fig. 6.

Fig. 8 is a central sectional view of the bell 55 swivel and hook structure.

Fig. 9 is a transverse section taken on line 9—9 of Fig. 4 and in the direction of the arrows.

In the drawings 10a and 10b indicate complementary castings suitably secured together as at 11. Each complementary casting upon its exterior is provided with a circular flange 12, see Fig. 4, and the interior 13 thereof serves as a drum for shoe engagement. Each casting includes a central opening 14 in which is mounted an anti-friction construction 15 with which is 10 associated a shaft 16 having projecting ends 17 which extend at opposite sides of the housing and therefrom. The shaft is shouldered as at 17a and each adjacent part of the housing includes an anti-friction retainer flange 14a. 15

Mounted on each end of the shaft and suitably keyed thereto, is a power transmitting disc, see Fig. 5, which includes an annular flange 18a, see Figs. 1 and 5, that telescopically receives the annular flange 12. Projecting from the interior 20 of the member 18 is a pair of diametrically positioned pins 19, see Fig. 5, or other suitable anchorages for the shoes 20 which are arcuate in form and may mount friction lining 21, or the like, said shoes being arranged for operative engagement with the interior 13 of the flange 12, as set forth in the before mentioned prior applications. These application disclosures, however, are subject to gravity acting on one shoe to release same and upon the other shoe to engage the 30 drum; hence, there results an unequal application.

The present invention seeks to insure simultaneous shoe movement and to a like degree and free the governor from gravity unbalancing.

Each shoe is pivotally connected at 22, see Fig. 5, to an arm 23 of a counterweight 24 pivoted at 25 to the member 18. The member 18 has an annular boss or shoulder 26 with a central opening 27 of reduced diameter therein. The annular boss or shoulder 26 is slotted as at 28 for key 29 for connection to the shaft 16. The end 17 of the shaft 16 nests in this annular boss, and the member 18 is secured against axial separation relative thereto by the screw 30 and washer 142— 45 see Fig. 1—the ends of the shaft being drilled and tapped for screw reception—see Fig. 4.

Rotatably mounted on the annular boss 26 is an annular collar 31 which is provided with two lugs 32 in alignment and oppositely directed. 50 Each lug supports a projecting pin or guide member 33 and the latter are slidably in the apertures 34 formed in ears 35 on each of the weights 24. Each shoe also is provided with cushion type stop, or rubber bumper 36 adapted to engage the 55

annular collar 31; thus, limiting the inward or radial movement of the weights toward each other and eliminating chatter. It has been found that a single weak spring construction is sufficient to secure shoe release movement of the weights since the weights in this instance are interconnected through the guide pins and annular collar. A duplicate spring construction, however, may be provided, if, as and when desired.

In Fig. 5 the weight 24 is shown apertured as at 37 and a weight returning spring 38 positioned in the aperture is anchored at 39 to a post rigid with the member 18. The opposite end is suitably secured to the member 24a carried by the apertured weight. To secure a balanced construction, the other counterweight is similarly apertured as at 37. To secure rigidity of mounting, if desired, the posts 19 and 25 may be connected by a tie member 25a.

This governor construction per se is capable of embodiment in the hoists illustrated and described in either of the copending applications and may be substituted therefor and as illustrated therein, the anchorage 39 may be of the adjustable character for adjusting spring tension. The spring shown may also serve as a load spring, since its force and effect must be overcome by the weights before shoe engagement occurs.

While the first mentioned copending application discloses a chain operable wheel as a source of power, the second application discloses a lever arm source of power and herein the invention is further illustrated as of the latter type.

The last mentioned application shows a tandem positioning immediately adjacent each other of the two levers. This application discloses the spaced positioning or balanced positioning of the two levers. These levers herein are indicated by the numeral 40 and are rotatably supported on a hub 41—see Fig. 1—which extends from plate 18 oppositely from the annular portion 26. The end of the hub bears against a washer 142 retained by screw 30. The lever arm at its free end is provided with a tiltable extension 42 pivotally connected at 43 therewith and portion 44 thereof serves as a friction gripping power applying shoe, see Fig. 2 which illustrates this cooperative relation which is more fully illustrated in Fig. 5 of the last mentioned copending application.

This relationship permits, in the clockwise stroke of lever arm 40—42, shoe 44 to engage initially the adjacent drum or wheel periphery 18a and continued movement causes drum rotation. Upon release from restraint imposed by cable 9, the constraint imposed by a returning and releasing spring serves initially to release shoe 44 from surface 18a and then serves to return arm 40—42 to the initial starting position without return of the drum.

It is to be understood that, if desired, the tiltable extension 42 may be of the adjustably extensible type. Each lever construction is tiltable as an entirety by an individual cable 9 or by a cable having its opposite ends connected to the free ends of the lever constructions 42. The operator by gripping the same and alternately pulling down with each hand, alternately rocks each lever arm for power application, the power being applied in the same direction, that is, for load elevation, and thereby the power, while intermittently applied to each lever arm construction, is substantially continuously applied to the shaft 16 although intermittently from opposite ends.

As stated in application Serial No. 16,365, the lever arm type of power application has the inherent advantage of permitting the hoist to be mounted at great heights and the power be applied through long light cables or ropes as distinguished from a long heavy continuous chain, such as is shown in the first mentioned application. It is, of course, to be understood that each complementary casting is provided with an upper stop and a lower stop limiting the extreme positions of movement of the lever construction. Each lever construction includes an extension 8—see Fig. 2 and illustrated in greater detail in Fig. 5 in application Serial No. 16,365. The lever returning spring 120 is suitably associated therewith and adjustably associated, if desired, and is illustrated in dotted lines in Fig. 2 and in greater detail in said application and said spring is anchored to the adjacent complementary casting member as at 119.

Each of the before mentioned applications includes a brake drum construction and a brake band operatively associated therewith. Herein, see Fig. 2, 45 indicates the drum construction rotatably mounted on the shaft 16, see Fig. 4, 25 within the housing and the drum is partially encircled by the band 46 provided with suitable lining 47, if, as and when desired. The casting is provided with lugs 48 that project inwardly and if desired, adjustable stops 49 may be associated therewith for limiting the release position of the brake band.

One end of the brake band is anchored as at 50—see Figs. 2 and 3. The other end of the band is recessed as at 51 and associated therewith is a coil spring 52, the latter being anchored as its opposite end by an adjustable type anchorage including the threaded member 53 that extends through slot 54 in the casting or housing and mounts washer 55 and nut 56 on the exposed end 40 of the member 53.

Enveloping the coil spring 52 is a sleeve 57 which, at its upper edge, contacts the "free" end 58 of the band. The lower end of the tube 57 is operatively engaged by an arm 59 of the lever 60 pivotally supported within the housing as at 61. To adjust this operative connection, there is provided the threaded member 62 and access thereto is had through the opening 63. The lower end of tube 57 is serrated as at 57a and the upper end 50 of screw 62 is tapered or wedge shaped so that rotation of the tube and/or the screw is prevented. The opposite end of the arm 60 has pivotally connected to it as at 64 the rod 65 terminating in the eye 66 that receives a cord or cable 66a which is the control cable for load lowering and return free-chain operation, as set forth in both of the prior copending applications. The rod 65 extends through the opening 67 in the casting.

Keyed to the shaft 16—see Figs. 2 and 4—is a ratchet wheel 68 having teeth 69 and nested within the overhanging portion 70 of the drum construction 45.

Pivotedly mounted—see Fig. 2—on the recessed face of the drum, are a plurality of pairs of ratchet engaging dogs 72 guidingly retained as at 73a and pivoted as at 73 and operatively constrained for ratchet engagement by the spring construction 74, or the like, anchored to the drum. Each pair of dogs and herein two pairs are illustrated, are so positioned about the drum such that—see Fig. 2—one pair of diametrical dogs engages the roots of a pair of ratchet teeth, while an intermediate 75

pair of diametrical dogs is in ratchet engagement but not in root association therewith.

Herein, since but one pair of intermediate dogs is illustrated, this intermediate pair is so positioned that it engages the ratchet teeth approximately half way between the root and crest thereof so that ratchet root engagement is effected by the dogs at ratchet half tooth distance and to this extent, as well as in the employment of a plurality of ratchet engaging dogs, the present application illustrates an improvement upon the copending applications and said improvement may be incorporated in either of the inventions disclosed in said copending applications without incorporating the other features of the present disclosure.

It will be understood that as set forth in the copending applications, when the brake band 47—see Figs. 2 and 4—is released, the brake drum 45 is free to rotate with the ratchet 68, the shaft 16, the sun gear 79 and the two members 81 and such rotation, when permitted, is restrained beyond a predetermined rate by the governor constructions, see Fig. 5, before mentioned, and in a similar manner as that set forth in the copending applications. When the lever arm 60 is not pulled downwardly (through release of cable 66a), the drum 77 is non-rotatably associated with the housing 10b through the pawl construction 91. Therefore, if power is not being applied to the shaft 17 for elevation of the load, the load is held by the ratchet dogs 72 carried by the brake drum 45, as well by pawl 91, hereinafter to be described.

Reference will now be had to the planetary transmission embodiment of the invention. This is best illustrated in Figs. 3 and 4 and therein positioned oppositely relative to the drum 45 is an internal ring gear 76 suitably and rigidly secured to a disc and drum 77 and 77a rotatably supported as at 78 relative to the shaft 16. A sun gear 79 has an annular shoulder 180 which rotatably supports said disc and drum, there being interposed therebetween the bushing 78. The opposite face of the disc portion 77 is provided with a plurality of arcuately spaced ratchet tooth type recesses 80 and herein four are illustrated, although more may be provided if desired. The purpose thereof and the associated mechanism will be set forth more fully hereinafter.

Meshing with the ring gear is a plurality of planetary pinion gears 81. These in turn mesh with the sun gear 79. Herein for simplicity but two are illustrated although more may be utilized if desired.

Rotatably supported on shaft 16 is the load chain engaging sprocket 82, the numeral 83 indicating a bearing therebetween. The sprocket has oppositely directed hub extensions 84 and 85, the latter being rigidly secured to a disc 86 that supports the pins 87 which pivotally support the planetary pinions 81. Thus power transmitted to shaft 16 from the lever arm or like construction (or the wheel and chain modification instead of the lever arm construction or a multiple form thereof) supplies the rotational power which is applied to the sun gear 79 by means of the key connection 88, or the like. Power to the planetary pinions 81 is applied to the chain engaging sprocket 82 by the disc 86. All the advantage of a planetary power transmission system are obtained in this form of the invention.

Reference will now be had more particularly to Fig. 3, wherein there is pivotally supported, on the pivot 90 rigid with the housing, a ring gear locking dog or pawl 91 having the recess engaging portion 92. The pawl 91—see Fig. 3—is recessed

at 91a and a spring 92a constantly urges the pawl 91 into disc engagement.

This dog prevents complete rotation of the ring gear in one and the load elevating direction because the portion 93 of the pawl constitutes a stop engaging the housing when the ring gear endeavors to rotate in a counterclockwise direction. Rotation in this direction, however, is permitted when the dog is retracted.

When the rod 65 is pulled down by the cable 66a to tilt lever 60 to release the brake band from the brake drum for load lowering, the spring 94 herein shown connected to the pivotal connection 64 at one end and connected as at 95 to the dog, insures retraction of the dog from the ratchet 15 recess 80 in the disc and drum 77 and the entire planetary system, sprocket gear and governor construction, or constructions, may rotate in the load lowering direction, provided there is no load on the chain. However, due to the friction 20 between gears, the governor construction usually does not rotate after pawl 91 is released from drum 77 for "free-chain" movement.

Due to the draft in recess 80 against pawl 91, drum 77 must rotate clockwise a slight amount 25 to free the pawl from the recess. This is impossible if there is a load on the chain because the load has to be lifted slightly to turn the drum 77 clockwise to clear pawl 91 relative to recess 80 and then permit spring 94 to withdraw the pawl. 30

When pawl 91 is withdrawn from the recess, and this, as stated, occurs only when lever 60 is tilted by rod 65 and there is no load on the chain, the drum 77 is free to rotate in either direction. Then if the chain be pulled in either direction (this being "free-chain" movement), only the sprocket 82, disc 86, planetary pinions 81 and drum 77 with ring gear 76 rotate. In other words, sun gear 79, shaft 16, discs 18, ratchet 68 and brake drum 45 do not rotate. This eliminates the friction of 40 the gearing as a load against "free-chain" movement.

When the tension on the cable 66a is released, the brake band 47 engages the brake drum 45 and the dog or pawl 91 may bear on the peripheral 45 surface of the disc and drum 77, unless the dog 91 should happen to register with one of the recesses 80. If it bears on the peripheral surface, then in the counterclockwise rotation, if any, the disc and drum 77 will rotate until one of the recesses 50 80 registers with the pawl 91 and picks up the pawl which locks the same to the housing and prevents further rotation of disc and drum 77.

For elevation of the load, the sprocket 82, the discs 18, the shaft 16 and the sun gear 79 rotate 55 clockwise. To secure such operation, the ring gear 76 and disc and drum 77 must be held stationary which is obtained by pawl 91 locking the disc and drum 77 to the housing 10a.

In the several figures, the housing is shown 60 provided at its upper end with an opening 95 which is adapted to receive a swivel hook or similar hoist support. Immediately therebeneath and at the opposite end of the housing, is the chain receiving opening 97 and the chain 98 extends upwardly therethrough and meshes with the teeth 99 of the sprocket gear 82.

The chain 98 has one end connected to the hoist casting and by an adjustable or relatively yielding arrangement, which is an improvement upon that 70 illustrated in Figs. 1 and 3 of the first mentioned copending application.

Herein, the chain 98—see Fig. 2—is pivotally connected at 100 to an arm 101 of a lever 102 pivotally supported as at 103. The opposite end of 75

the lever, as at 104, is connected to one end of the spring 105, connected at its opposite end to a casing anchorage 106. This may be of adjustable character for adjusting spring tension. When 5 the chain 98 is fully extended, the load being dropped or lowered, as illustrated in Fig. 2, continued pulling on the chain in the load lowering direction tilts the lever 101—102 clockwise in opposition to spring 105 to extend the latter, thus 10 cushioning the pull on the chain anchorage 100 at the end of the load lowering movement of the chain 98.

As shown in Fig. 2, the casing or housing is apertured as at 107 and suitably mounted in said 15 aperture is a member 108.

In Fig. 2 there is illustrated a lever stop in the form of a bracket 109 suitably secured to the curved portion 109a of each housing. The laterally offset portion 110 of bracket 109 serves as a 20 stop for lever 40. Portion 110 is apertured as at 119 to anchor one end of the lever arm returning spring 120, the other end of which is suitably and adjustably secured as at 118a to an extension 118 of the lever 40—see Figs. 1 and 2.

25 Spring 120, see Fig. 2, associated with the lever 40 automatically returns it to its elevated and initial position, and a stop 140 on the housing is provided to limit the return movement of the lever 40 and the initial position thereof.

30 Portion 117—see Fig. 2—upon member 113 also serves as a chain shedder and spacer preventing interference between the runs of the chain when there is slack in the chain between the sprocket and anchorage 100.

35 Member 108 has a lateral offset portion 111—see Fig. 2—within the casing and projecting therefrom is the portion 112 which pivotally supports the chain cushioning anchoring lever 102. Portion 112 is extended as at 113 and is centrally 40 apertured as at 114—see Fig. 4—and the hub 84 of the chain sprocket 82 is rotatably mounted therein. A relatively arcuate flange 116 extends laterally from the portion 113 and forms a chain guard and thus prevents the chain from doubling 45 within the housing. It—see Fig. 2—also serves as a stop for chain anchorage lever arm 102 and prevents interference between chain 98 and spring 105. Guard 116 also prevents escapement of the chain 98 from sprocket engagement.

50 In Figs. 2 and 6, the load chain 98 is shown terminating at the load end in a bell shaped swivel and hook, 150 indicating the split bell portions—see Fig. 8—and 151 the eye portion to which the last link 152 of the chain is secured as at 153. 55 The bell portion has flange 154 thereon serving as a stop and the retaining band 155 secures the parts together to insure retention of hook 156 swivelly supported by thrust bearing 157, the hook having the head portion 158.

60 As shown in Fig. 4, slightly below the level of disc and drum 77 and ring gear 76—see Fig. 6 for the necessity for sufficient clearance to provide for lubrication retention—the housing 10a—10b is provided with an apertured stop, see Fig. 9, the 65 aperture thereof being elongated to conform to the elongated opening 97. The stop is indicated by 170 and may be formed integral with the castings, welded thereto or otherwise rigidly secured thereto. The elongated portion thereof is apertured at 171 and is flared as at 172 to accommodate the upper portion of the bell swivel. As shown in Figs. 4 and 6, the entire bell portion is nestable within housing 10a—10b and the hook 156 has only its shank nested while the hook is exposed. Stop 170 limits further upward chain 75

movement when the bell swivel engages this stop.

In Fig. 6, the skeletonized section illustrates a substantially enclosed form of the invention, although only one side thereof is illustrated. In said figure, 210 indicates the housing, 212 the 5 governor drum, the annular flange on the power disc carried by extension 211 of shaft 216 being omitted for clearness. An auxiliary housing 200 is secured to housing 210 at 211 by cap screws or the like. The housing 200 peripherally encloses the 10 disc (not shown) and the shaft anchorage. The outer edge 201 is stepped at 202 to nest the cover plate 203 secured thereto by cap screws, or the like, 204.

Housing 200 includes a recess 205 which terminates in end walls 206 and 207. Wall 206 serves as the upper stop for limiting the initial and normal upper position of lever 240 while wall 207 limits the lower position thereof. In this form of the invention, the auxiliary housing 200 and the 20 plate 203 encloses the lever return spring omitted in Fig. 6 for clearness. Housing 200 includes a lug 208 apertured at 219 to form an anchorage for the lever returning spring.

In this form of the invention, the auxiliary 25 housing eliminates the upper stop 140—see Fig. 1—the lower stop 110 and its spring anchorage 119 shown in the first and unenclosed or non-protected form of the invention.

In this form of the invention, see Fig. 6, there 30 is also disclosed disc 277 which has an annular projection 277a projecting slightly beyond ring gear 276 and the latter is nested and press fitted therein. The projecting portion includes groove 279b and disc 287 is shouldered at 287a. Annular plate 287b is sprung into groove 279b and rides free in the shouldered portion 287a of disc 287. Thus, the planetary transmission is relatively enclosed and the gears may be packed with heavy lubricant which is prevented by this 40 enclosed arrangement from escapement to the sprocket, chain and brake structure.

To permit repacking of the construction, the plate portion 210c is apertured as at 210d which aperture is slightly larger than the threaded aperture 277b in the drum disc 277 and said threaded aperture receives a screw plug 277c. The power disc 218 in juxtaposition thereto, is illustrated in Fig. 6 by dotted lines. Only a portion thereof is shown. Said disc has the lever gripped 50 surface 218a. The disc proper is apertured as at 218b and said aperture is larger in diameter than aperture 210d, which, in turn, preferably is larger in diameter than aperture 277d. A screw plug 218c is threaded in the threaded aperture 218b 55 of the disc 218 and said aperture is so positioned relative to the mounting of the governor shoe that it can register with the aforesaid apertures without interference from the shoes.

When repacking is desired or necessary, plug 60 218c is removed and the aperture 218b aligned with aperture 210d and then the screw plug 277b is positioned in alignment with said apertures and then removed. The usual grease supplying mechanism may then be applied to the registering apertures to supply any deficiency. The aperture 210d is shown illustrated at the top of the hoist housing. In actual practice, however, it preferably would be positioned diametrically opposite, to wit, near the lowest point so 70 that the old grease could readily be removed by flushing, and the like, and then the new grease substituted whenever it is not desired to make a mere addition or supply "make-up" to the lubricant then in use.

In Fig. 7 is illustrated a modified form of the invention, intermediate in character between the unprotected and substantially fully protected forms of the invention. In this intermediate form, only the lever returning spring is enclosed. In this figure, 318 indicates the power disc, 340 the power lever, 310 the housing proper, 398 the load chain, 380 a casing guard or auxiliary housing enclosing the returning spring (not shown) for lever 340 retained by cap screw 330 in the end of the main shaft not shown. The lower end of the auxiliary housing is inturned to lie adjacent flange 318a of disc 318 and is secured to housing 310 by a screw 301 through the bracket, 15 constituting the lower stop (see same at 110 in Fig. 2).

If desired, this form of the invention may include the planetary system lubrication retention construction, illustrated in Fig. 6.

20 Each of the modifications shown in Figs. 6 and 7 may also include the load hook bell swivel and stop structure and the protective interior stop or guard as illustrated in Figs. 4 and 6.

While the invention has been described in great detail in the foregoing specification relative to the improvements over the two before mentioned applications, and while it has been pointed out that certain of these improvements may be associated in a hoist of the general character illustrated and described in the copending applications, as well as those illustrated and described in the prior patents before mentioned, and whereas several modifications of the present disclosure have been mentioned herein, it is to be understood that such detail description is to be considered illustrative and not restrictive in character and these modifications, whether utilized individually or collectively or as substitutions, and all other modifications thereof which will readily suggest themselves to persons skilled in this art, are all considered to be within the broad scope of this invention, reference being had to the appended claims.

The invention claimed is:

45 1. In a chain hoist, the combination with a housing, a load chain engaging gear, an elevating shaft therefor rotatable in the housing and having ends projecting therefrom, and brake means operatively associated with the load gear 50 permitting load lowering, of rotatable members carried by the housing projecting ends of the shaft, and individual governor means associated with each member regulating the load lowering movement of the gear.

55 2. A device as defined by claim 1, characterized by the addition of a lever arm adjacent each rotatable member, a one-way operable locking connection therebetween for rotating the adjacent member when the arm is rocked in one direction, and means normally constraining the arm toward movement in the opposite direction, said one-way connection being ineffective for locking in said opposite direction.

60 3. A device as defined by claim 1, characterized by the addition of a lever arm adjacent each rotatable member, a one-way operable locking connection therebetween for rotating the adjacent member when the arm is rocked in one direction, means normally constraining the arms toward movement in the opposite direction, said one-way connection being ineffective for locking in said opposite direction, and a planetary transmission system interposed between said shaft and load chain gear.

70 4. In a chain hoist, the combination with a

housing, a load chain engaging gear, an elevating shaft for the gear rotatable in the housing, and brake means operatively associated with the gear permitting load lowering, of a rotatable member carried by the housing projecting end of the shaft, governor means associated with said member for regulating the load lowering movement, and a planetary transmission system between said shaft and load chain gear.

5 5. In a chain hoist, the combination with a load chain engaging gear, means for rotating the gear for chain movement, a ratchet and pawl structure for sustaining the load when said means is not elevating, a brake structure operatively associated with the ratchet and pawl structure for insuring ratcheting action in load elevation, load sustainment when not elevating and releasably associated therewith for load lowering, and a control member for the brake structure, of a rotatable power member, and a planetary transmission system between the power member and the gear.

10 6. In a chain hoist, the combination with a load chain engaging gear, means for rotating the gear for chain movement, a ratchet and pawl structure for sustaining the load when said means is not elevating, a brake structure operatively associated with the ratchet and pawl structure for insuring ratcheting action in load elevation, load sustainment when not elevating and releasably associated therewith for load lowering, and a control member for the brake structure, of a tube, a coiled spring therein, said brake structure including a band having one end connected to said spring, the latter having a relatively permanent anchorage for its opposite end, and a lever connected to the control member and having one end operatively associated with one end of the tube, said band having a tube bearing portion adjacent the spring connection thereto and operatively engageable by the opposite end of the tube upon member operation.

15 7. In a chain hoist, the combination with a load chain engaging gear, means for rotating the gear for chain movement, a ratchet and pawl structure for sustaining the load when said means is not elevating, a brake structure operatively associated with the ratchet and pawl structure for insuring ratcheting action in load elevation, load sustainment when not elevating and releasably associated therewith for load lowering, and a control member for the brake structure, of a second ratchet and pawl structure for sustaining the load when said means is not elevating, and an operative connection between the latter and the control member for disassociating the ratchet and pawl connection of the second structure upon brake structure release.

20 8. In a chain hoist, the combination with a load chain engaging gear, means for rotating the gear for chain movement, a ratchet and pawl structure for sustaining the load when said means is not elevating, a brake structure operatively associated with the ratchet and pawl structure for insuring ratcheting action in load elevation, load sustainment when not elevating and releasably associated therewith for load lowering, and a control member for the brake structure, of a rotatable power member, a planetary transmission system between the member and the gear, a second ratchet and pawl structure for sustaining the load when said means is not elevating, and an operative connection between the latter and the control member for disassociating the ratchet and pawl connection of the second structure upon brake structure release.

9. In a chain hoist, the combination with a load chain engaging gear, means for rotating the gear for chain movement, a ratchet and pawl structure for sustaining the load when said means is not elevating, a brake structure operatively associated with the ratchet and pawl structure for insuring ratcheting action in load elevation, load sustainment when not elevating and releasably associated therewith for load lowering, and 10 a control member for the brake structure, of a second ratchet and pawl structure for sustaining the load when said means is not elevating, an operative connection between the latter and the control member for disassociating the ratchet and pawl connection of the second structure upon 15 brake structure release, a tube, a coiled spring therein, said brake structure including a band having one end connected to said spring, the latter having a relatively permanent anchorage for its opposite end, and a lever connected to the control member and having one end operatively associated with one end of the tube, said band having a tube bearing portion adjacent the spring connection thereto and operatively engageable by the opposite end of the tube upon member operation.
10. In a hoist, the combination with a rotatable shaft, a housing from which the shaft projects, a drum rigid with the housing and a pair of diametrically arranged substantially identical shoes for drum engagement, of a member rotatable by the shaft and to which opposite ends of the shoes are secured, substantially identical weighted lever arms symmetrically and pivotally supported by the member and symmetrically connected to the other ends of the shoes, means operatively and symmetrically connecting said arms together for simultaneous and like movement of the arms irrespective of gravitation, and spring means for opposing lever movement caused by 40 centrifugal action of said weighted levers.
11. In a hoist, the combination with a load chain gear, a rotatable member for rotating same, and a brake construction, one portion thereof being normally relatively stationary and relative 45 to which the member is rotary, the other portion being manually movable for first portion release, of ratchet and pawl means operatively interposed between the brake construction and gear permitting gear rotation for load elevation, gear re-tension for sustaining the load, and upon manual movement permitting controlled gear rotation for load lowering by said brake structure, said ratchet and pawl means including a plurality of pairs of arcuately spaced dogs, the spacing between dogs of different pairs being unequal whereby when one pair of dogs has ratchet tooth root engagement, another pair will have ratchet engagement other than tooth root engagement.
12. In a hoist, the combination with a load 50 chain engaging gear, a shaft for rotating same, manually controlled means for load sustainment when load elevation is not desired and permitting load lowering subject to the manual control, and a housing therefor, of a planetary system interposed between the gear and shaft and including a ring gear structure having a ratchet tooth arrangement, a ratchet pawl pivotally supported by the housing normally permitting ring gear rotation in one direction and preventing reverse rotation in the opposite direction, and a connection between the pawl and manually controlled means to remove the ratchet pawl rotation restraint.
13. In a chain hoist, the combination with a 55 housing, a load chain, a chain engaging gear, and a chain elevating shaft, of a member included within the housing and relatively rigidly mounted therein, said member having an arcuate chain guard surface adjacent to and partially surrounding but spaced from the chain gear, an 60 arm pivotally supported in juxtaposition to the guard surface and eccentric of the chain gear axis and connected at one end to the chain, and yielding means connected at one end to the housing and at the opposite end to the other end to the 65 housing and at the opposite end to the other end to said arm.
14. In a chain hoist, the combination with a housing, a load chain, a chain engaging gear, and a chain elevating shaft, of a member included within the housing and relatively rigidly mounted 70 therein, said member having an arcuate chain guard surface adjacent to and partially surrounding but spaced from the chain gear and a portion parallel to a plane transverse to the gear axis and having an annular bearing coaxial with the chain gear.
15. In a chain hoist, the combination with a housing, a load chain, a chain engaging gear, and a chain elevating shaft, of a member included within the housing and relatively rigidly mounted 75 therein, said member having an arcuate chain guard surface adjacent to and partially surrounding but spaced from the chain gear, an arm pivotally supported in juxtaposition to the guard surface and eccentric of the chain gear axis and connected at one end to the chain, and yielding means connected at one end to the housing and at the opposite end to the other end to the 80 housing and at the opposite end to the other end to said arm, said member having an annular bearing coaxial with the chain gear.
16. In a chain hoist, the combination with a housing, a load chain, a chain engaging gear, and a chain elevating shaft, of a member included therein, said member having an arcuate chain guard surface adjacent to and partially surrounding but spaced from the chain gear, said member having an annular bearing coaxial with the shaft and operatively supported thereby.
17. In a chain hoist, the combination with a housing, a load chain, a chain engaging gear, and a chain elevating shaft, of a member included within the housing and relatively rigidly mounted therein, said member having an arcuate chain guard surface adjacent to and partially surrounding but spaced from the chain gear, an arm pivotally supported in juxtaposition to the guard surface and eccentric of the chain gear axis and connected at one end to the chain, and yielding means connected at one end to the housing and at the opposite end to the other end to said arm, said member having an annular bearing coaxial with the shaft and operatively supported thereby.
18. In a chain hoist, the combination with a housing, a load chain, a chain engaging gear, and a chain elevating shaft, of a member included within the housing and relatively rigidly mounted therein, said member having an arcuate chain guard surface adjacent to and partially surrounding but spaced from the chain gear, said member having an annular bearing, said gear having a hub portion seatable therein, said shaft rotatably supporting said chain gear, and a planetary system operatively connected to said gear and shaft for rotation of the former by the latter.
19. In a chain hoist, the combination with a housing, a load chain, a chain engaging gear, and a chain elevating shaft, of a member included within the housing and relatively rigidly mounted therein, said member having an arcuate chain

- guard surface adjacent to and partially surrounding but spaced from the chain gear, an arm pivotally supported in juxtaposition to the guard surface and eccentric of the chain gear axis and connected at one end to the chain, yielding means connected at one end to the housing and at the opposite end to the other end to said arm, said member having an annular bearing, said gear having a hub portion seatable therein, said shaft rotatably supporting said chain gear, and a planetary system operatively connected to said gear and shaft for rotation of the former by the latter.
20. In a free chain hoist, the combination of a planetary power system, means preventing reverse rotation thereof, a load gear, power means for the system, a brake structure for controlling load lowering movement of the gear, and manually operable means controlling the brake structure and the reverse rotation preventing means to secure free chain action in the load lowering direction.
21. In a chain hoist, the combination with a housing, a load chain engaging gear, an elevating shaft therefor rotatable in the housing and having an end projecting from the same, of a rotatable member carried by the exposed end of the shaft, a lever arm oscillatable relative to said member, a one-way driving connection therebetween, means constraining said lever arm toward initial position, and guard means for the last-mentioned means.
22. In a chain hoist, the combination with a housing, a load chain engaging gear, an elevating shaft therefor rotatable in the housing and having an end projecting from the same, of a rotatable member carried by the exposed end of the shaft, a pivotal support for a lever arm, a lever arm oscillatable relative to said member, a one-way driving connection therebetween, means constraining said lever arm toward initial position, and guard means for the last mentioned means and arranged to determine the initial and final positions of the lever arm.
23. In a chain hoist, the combination with a housing, a load chain engaging gear, an elevating shaft therefor rotatable in the housing and having an end projecting from the same, of a rotatable member carried by the exposed end of the shaft, governor means associated with the member for regulating load lowering movement, a pivotal support for a lever arm, a lever arm oscillatable relative to said member, a one-way driving connection therebetween, means constraining said lever arm toward initial position, and guard means for the last mentioned constraining means.
24. In a chain hoist, the combination with a housing, a load chain engaging gear, an elevating shaft therefor rotatable in the housing and having an end projecting from the same, of a rotatable member carried by the exposed end of the shaft, governor means associated with the member for regulating load lowering movement, a pivotal support for a lever arm, a lever arm oscillatable relative to said member, a one-way driving connection therebetween, means constraining said lever arm toward initial position, and guard means for the last mentioned constraining means and arranged to determine the initial and final positions of the lever arm.
25. In a chain hoist, the combination with a load chain engaging gear, a planetary transmission for rotating same, said transmission including planetary pinions, a revoluble support there- for, a ring gear meshing with the pinion, and a sun gear meshing with the pinion gears, and a transmission rotating shaft, of a support for the ring gear and arranged as closure for one end of the transmission, and including an annular projection nesting the ring gear therein and including a recessed coaxial portion, said support including a recessed coaxial portion, and an annular sealing washer rigidly mounted in one recess and nestable in the other for transmission lubricant retention without interference with the relative rotation of the support and ring gear.
26. A device as defined by claim 4, characterized by the brake means being positioned adjacent one end of the shaft, the load chain gear intermediate the ends and brake means and transmission system for balancing, the latter being positioned adjacent the other end of the shaft, said shaft projecting from the housing at opposite ends, and by the addition of an additional rotatable member upon the other projecting end of the shaft, and governor means for the second rotatable member, said governor means and rotatable members being relatively balanced.
27. A device as defined by claim 25, characterized by the addition of a housing adjacent the transmission, said housing including an aperture and said ring gear support including an aperture, said apertures being arranged for registration in one relative position, and the addition of closure means in the latter aperture and removable through the former aperture for lubricant replenishment.
28. A device as defined by claim 25, characterized by the addition of a housing adjacent the transmission, said housing including an aperture and said ring gear support including an aperture, said apertures being arranged for registration in one relative position, and the addition of closure means in the latter aperture and removable through the former aperture for lubricant replenishment, and by the further addition of a power transmitting disc having an aperture therein, and closure means for said last mentioned aperture, the latter aperture being adapted for registration in one position with the other two registrable apertures for lubricant replenishment.
29. A device as defined by claim 4, characterized by the brake means being positioned adjacent one end of the shaft, the transmission system being positioned adjacent the other end of the shaft, and the load chain gear being positioned intermediate the shaft ends and between the brake means and the transmission system for hoist balancing purposes, and by the addition of a substantially centrally positioned housing support.
30. In a chain hoist including a housing arrangement, a load chain depending therefrom, chain moving means within the housing including a power shaft having an exposed end, a control mechanism for the chain moving means and within the housing including a control member projecting therefrom for manual operation, a governor structure operatively interposed between the shaft and housing, a planetary system interposed between the shaft and housing, a power wheel on the exposed end of the shaft, and lever means operatively associated with the power wheel for manually rotating the shaft in a load elevating direction.
31. In a chain hoist including a housing arrangement, a load chain depending therefrom, chain moving means within the housing includ-

ing a power shaft having an exposed end, a control mechanism for the chain moving means and within the housing including a control member projecting therefrom for manual operation, a 5 governor structure operatively interposed between the shaft and housing, a planetary system interposed between the shaft and housing, a power wheel on the exposed end of the shaft, and means operatively associated with the power wheel for 10 manually rotating the shaft in a load elevating direction.

32. In a chain hoist, the combination with a 15 housing, a load chain engaging gear, an elevating shaft for the gear rotatable in the housing, and brake means operatively associated with the gear permitting load lowering, of a rotatable member carried by the housing projecting end of the 20 shaft, governor means associated with said shaft and housing for regulating load lowering movement, and a planetary transmission system between said shaft and load chain gear.

33. A device as defined by claim 10, characterized by the addition of a brake structure for holding the load stationary against lowering and 25 releasable for load lowering.

34. A device as defined by claim 10, characterized by the addition of a planetary transmission operatively associated with the rotatable shaft.

35. A device as defined by claim 10, characterized by the addition of a brake structure for holding the load stationary against lowering and releasable for load lowering, and a planetary transmission operatively associated with the rotatable 30 shaft.

36. In a chain hoist, the combination with a load chain engaging gear, a planetary transmission for rotating same, said transmission including planetary pinions, a revolvable support therefor, a ring gear meshing with the pinions, and a 40 sun gear meshing with the pinions, a transmission rotating shaft, a support for the ring gear and arranged as a closure for one end of the transmission and including an annular projection nesting the ring gear therein and including a 45 recessed coaxial portion, and an annular sealing washer rigidly mounted in the recess for transmission lubricant retention without interference with the relative rotation of the support and ring gear.

37. A device as defined by claim 36, characterized by the addition of a brake structure, a one-way driving connection between the same and the shaft for load suspension when the shaft is not elevating, and means releasably associated with 50 the brake structure for load lowering.

38. A device as defined by claim 36, characterized by the addition of governor means associated with said shaft and arranged to restrict the rate of load lowering.

39. A device as defined by claim 36, characterized by the addition of a brake structure, a one-way driving connection between the same and the shaft for load suspension when the shaft is not elevating, means releasably associated with the 60 brake structure for load lowering, and governor means associated with said shaft and arranged to restrict the rate of load lowering, and when the brake structure is released.

40. In a chain hoist, the combination with a 70 load chain engaging gear, means for rotating the

gear for chain movement, a ratchet and pawl structure for sustaining the load when said means is not elevating, a brake structure operatively associated with the ratchet and pawl structure for insuring ratcheting action in load elevation, load sustainment when not elevating, and releasably associated therewith for load lowering, and a control member for the brake structure, of a tube, a coil spring therein, said brake structure including a band having one end connected to said 10 spring, the latter having a relatively permanent anchorage for its opposite end, and lever means at one end connected to the control member and having the other end operatively associated with the tube for tube movement, said band having a 15 tube bearing portion adjacent the spring connection to the band and operatively engageable by the tube upon member operation through said lever means.

41. In a chain hoist, the combination with a 20 load chain engaging gear, means for rotating the gear for chain movement, a pawl and ratchet structure for sustaining the load when said means is not elevating, a brake structure operatively associated with the ratchet and pawl structure 25 for insuring ratcheting action in load elevation, load sustainment when not elevating and releasably associated therewith for load lowering, and a control member for the brake structure, of a second ratchet and pawl structure for sustaining the 30 load when said means is not elevating and operatively connected between the latter and the control member for disassociating the ratchet and pawl connection of the second structure upon 35 brake release, a tube, a coil spring therein, said brake structure including a band having one end connected to said spring, the latter having a relatively permanent anchorage for its opposite end, and lever means connected at one end to the control member and having the other end operatively 40 associated with the tube for tube movement, said band having a tube bearing portion adjacent the spring connection to the band and operatively engageable by the tube upon member operation through 45 said lever means.

42. In a hoist, the combination with a load chain gear, a rotatable member for rotating same, and a brake construction, one portion thereof being normally relatively stationary and relative to which the member is rotary, the other portion being manually movable for first portion release, of ratchet and pawl means operatively interposed between the brake construction and gear, permitting gear rotation for load elevation, gear retention for sustaining the load, and upon manual movement permitting controlled gear rotation for load lowering, and a planetary transmission operatively interposed between said load gear and member and through which rotary power is applied to the load gear from the rotatable member for load elevation, such inter-positioning being independent of the brake construction connection to the load gear, said ratchet and pawl means including a plurality of pairs of arcuately spaced dogs, the spacing between dogs of different pairs 65 being unequal, whereby when one pair of dogs has ratchet tooth engagement, another pair will have ratchet engagement other than tooth root engagement.

FREDRICK W. COFFING. 70
